UNITED STATES PATENT OFFICE.

TOLBERT K. TIFFANY, OF TRENTON, NEW JERSEY, ASSIGNOR TO JAMES H. BELL, OF PHILADELPHIA, PENNSYLVANIA.

INCUBATOR.

Application filed May 20, 1925. Serial No. 31,511.

This invention relates to incubators, and is concerned with improvements calculated to facilitate manipulation of the eggs for positional change as required periodically 5 during incubation.

More specifically stated, one object of my invention is to provide, for use in connection with an incubator of the cabinet type, means for supporting a comparatively large number 10 of egg trays in compact sequence and in multi-columnar formation; said means affording a department or section capable of adjustment for the purpose above mentioned, as well as a department or section which is 15 serviceable as a nursery whereto the trays may be transferred for hatching of the eggs.

Another object of my invention is to enable, in an incubator with the aforesaid appointments, individual access to the different 20 departments or sections of the tray supporting structure.

Other objects and attendant advantages accruing to my invention will be apparent from the detailed description hereinafter of 25 a typical embodiment as illustrated in the accompanying drawings.

Fig. I is a view, partly in front elevation and partly in longitudinal section, of the incubator.

30 Fig. II is a cross section on a larger scale of the organization, taken approximately as indicated by the arrows II—II in Fig. I, and with the egg-trays in horizontal position.

35 Fig. III is a partial front elevation of the tray supporting structure; and,

Fig. IV, is a fragmentary perspective illustration showing the means whereby an 40 ordinary egg tray is adapted for use in the nursery section of the tray supporting structure.

With reference to the drawings, the numeral 1 indicates the housing of the incubator, the same affording an elongated incubating 45 chamber 2 capable of accommodating, side by side, a number (in this instance two) of egg-tray-supporting racks each comprehensively designated 3. Fresh air enters the incubator 1 at opposite ends through grated 50 openings 4 that communicate with ducts 5 extending laterally into the hollow base 6 of the structure and in turn communicating, through ports 7, with the hollow end walls 8 at their bottoms. As shown, these walls 55 8 are each subdivided interiorly by an in-

termediate partition 9, into separate vertical branches 10 and 11, the air passing upward in the branch 10, over the top of the partition 9, then downward in the branch 11 and finding its way into the incubating 60 chamber 2—at the bottom—through an opening 12. Concurrent with upward travel in the branches 10 in opposite end walls 8, the air is heated by contact with coil banks 13 therein, said banks being connected between flow and return mains 14, 15 extending 65 respectively across the top of the structure and through the hollow base 6. After coursing horizontally through the chamber 2 from the ends thereof, the two opposed 70 air streams make their exit by way of a centrally-located flue 16 whereof the lower portion 17 is coextensive in width with said chamber, while the upper portion is in the form of a pipe 18 which leads to the exterior 75 through the roof of the incubator enclosure 1, entry of air into the flue 16 being via bottom openings 19, 19 at opposite sides thereof. An auxiliary bank 20 of heating coils in the lower portion 17 of the flue 16 80 serve to induce upward draft in the pipe 18, and thereby stimulate circulation of air through the chamber 2 as explained. This circulation is however subject to automatic governance by thermostats 21 which are located 85 within the chamber 2 and actuate dampers 22, 23 arranged to cooperate respectively with exhaust outlets 24, 25 extending through the roof of the structure, the outlets 24 leading directly from the 90 chamber, and the outlets 25 from the air flow passages 10, 11 in the end walls 8. As a result of this arrangement, in the event of a temperature rise in the chamber 2 beyond a predetermined degree due, for example, 95 to animal heat given off by the eggs during the latter stages of incubation, the exhaust openings 24, 25 will be uncovered to a greater or lesser extent to compensatively vent a portion of the heated air as required. The 100 auxiliary coil bank 20 is connected in parallel with the main heating coil banks 13 across the flow and return mains 14, 15; and each of the several coils thus receives its proper apportionment of the flow of heating 105 medium for which I prefer to employ hot water in the present instance. The features thus far described form the subject matter of a copending application under Serial Number 31,510 filed by me simultaneously 110

herewith, and have been referred to with a view only toward facilitating a general understanding of the disclosures which follow.

5 Referring now to the egg tray racks 3, it will be best observed from Fig. I that these are exact counterparts of one another, and accordingly, in order to avoid the inconvenience of repetitive description, reference to them will, for the time being, be made in the singular. As shown, each rack 3 comprises a lower or subsection 30 for nursery trays, and a superposed upper section 31 for incubating trays. The subsection 30 as best shown in Fig. III embodies a rigid frame constructed wholly from structural angles with upper and lower horizontals 32, corner verticals 33, and intermediate central uprights 34, the back and 10 sides of the frame being enclosed by screening 35, see Fig. II. To the corner verticals 33 and the central uprights 34 are secured laterally-extending slide rails 36 which are coordinated in pairs to support the egg trays 15 indicated at 37, in the double-columnar arrangement illustrated. The trays 37 are of the typical variety ordinarily employed during incubation; but in order to adapt them for use as nursery trays in the nursery section 30, I provide detachable supplemental front boards 38 to close up the necessary head spaces which must be provided for the newly-hatched chicks. The supplemental boards 38 are equipped with clips 39 designed to engage over the top edges of the front walls 40 of the trays 37 in a manner obvious from Fig. IV, and also with finger knobs 41—Fig. III—for convenience in 20 withdrawing the trays.

25 40 The upper section 31 of the tray rack 3 embodies a vertical central member 42 fashioned to rectangular configuration (see Fig. II) preferably from flat bar metal, and spaced parallel end members 43. Extending 45 between the central member 42 and the spaced end members 43, respectively, are pivotally-connected cross members 44 upon which are secured slide rails 45 that extend laterally of the rack 3 and cooperate in 50 pairs to support a double column of the egg trays 37, the arrangement and grouping thus being the same as in the nursery section 30. The upper rack section 31 is sustained by brackets 46 extending from the front and 55 rear ends of the subsection 30, said brackets affording clevices 47 at their upper ends for horizontal pins 48 that serve as fulcrum bearings centrally beneath the lowermost pair of cross members 44 of the two adjacent vertical series. By such an arrangement, it will be apparent that the upper rack section 31 may be adjusted through relative longitudinal shifting between its verticals 42, 43, and the trays 37 thus transposed from 60 the horizontal position of Figs. II and III

to angular positions either in one direction or the other as shown in Fig. I so that the yolks of the eggs are positionally shifted as required from time to time during the process of incubation. As a means to stabilize 70 the movement of the upper section 31 of the tray rack during adjustment, I utilize a pair of fixed spaced rods 50 that extend from top to bottom of the incubating chamber 2. The rods 50 serve as guides for the 75 intermediate vertical rectangular members 42 of the section 31, the upper and lower horizontals of said section having correspondingly spaced aligned apertures for accommodating the rods with sufficient clearance to insure free movement. The mechanism employed to adjust the rack section 31 includes a screw 51 which is affixed to the lower end of one of the vertical members, preferably centrally of the intermediate 80 member 42 as shown. This screw 51 is engaged by an axially-threaded nut or collar 52 which is positionally fixed and supported for rotation in a bracket 53 secured to the top of the subsection 30 of the rack 3. The 85 collar 52 is circumferentially toothed to function as a worm wheel for meshing engagement with a drive worm 54 fast on an actuating shaft 55 having journal support jointly in the bracket 53 and a cooperating 90 bearing 56, the latter also mounted on the top of the subsection 30. From Figs. I and II it will be noted that the actuating shafts 55 of the two tray racks 3 extend to the exterior of the incubator housing through its 95 front wall, the squared outer ends 57 of said shafts being accessible in counter-bores 100 58 so as to permit of engagement by a detachable operating handle such as shown at 59.

105 In order that the two tray racks 3 may be individually accessible, the incubator housing 1 is equipped at the front with two groups of closures, each such group composed of double upper doors 60 swingable 110 outward about vertical hinges 61, and a lower door 62 swingable upward on horizontal hinges 63. The upper doors 60, permit access separately to the upper section 31 of the tray rack 3; and said doors are glazed 115 as conventionally illustrated, enabling observation of the eggs from time to time during the incubating period without necessitating their exposure to the chilling influence of outside atmosphere. The lower door 62 in a like manner permits access 120 separately to the subsection 30 of the tray rack 3, said door being preferably made solid and opaque to exclude excessive light during the hatching phase of the incubating 125 period.

Having thus described my invention, I claim:

130 1. A rack for incubators comprising a vertical central member, spaced parallel end

- members, a series of pivotally connected tray-supporting cross members, fulcrum supports extending centrally beneath the lowermost of each series of cross members, 5 and spaced rods to guide the central member to longitudinal movement, whereby the rack as a whole may be adjusted so that the trays of the two columns may be shifted to different complemental angular positions.
- 10 2. A tray rack for incubators comprising a central and parallel vertical members in spaced relation, pivotally-connected cross members extending transversely between the several vertical members to support a multiplicity of egg trays in multi-columnar formation, fulcrum supports centrally beneath the lowermost cross members of each series of cross members, and spaced rods to stabilize the central member during longitudinal movement; in combination with means enabling adjustment of the rack including a screw on one of the vertical members, a positionally fixed nut cooperating with the screw, and connections whereby the 25 nut may be rotated from the exterior of the incubator.
3. In an incubator the combination of racks comprising stationary nursery sec-
- tions and relatively movable incubating sections supported thereover by fulcrum bearings on the nursery sections, said incubating sections embodying pivotal tray supports adapted for simultaneous movement in columnar series. 30
4. A tray rack for incubators comprising a lower section for nursery trays, said section including rigid fulcrum-bearings for columnar tiers of egg-tray supporting members, and means adapted to slidably rock the respective columnar tiers of egg-tray supporting members on the bearings aforesaid, for the purpose specified. 35
5. A tray rack for incubators comprising a lower rigid section for nursery trays, said section including stationary clevis-bearings 40 for columnar tiers of pivotal egg-tray supporting members, and mechanism actuatable to slidably rock the respective columnar tiers of egg-tray supporting members on the clevis-bearings to effect their reverse inclination with respect to the horizontal. 45
- In testimony whereof, I have hereunto signed my name at Trenton, New Jersey, this fourteenth day of May, A. D. 1925. 50

TOLBERT K. TIFFANY.
